UNITED STATES PATENT OFFICE.

MORRIS J. HOFFMAN, OF CHICAGO, ILLINOIS.

PRINTING DEVICE.

Application filed November 9, 1923 Serial No. 673,641.

To all whom it may concern:

Be it known that I, MORRIS J. HOFFMAN, a citizen of the United States, and a resident of Chicago, Cook County, Illinois, have invented certain new and useful Improvements in Printing Devices, of which the following is declared to be a full, clear, and exact description.

This invention relates to printing devices, and its primary object is to provide a printing device with a storage space for containing type carriers in which type slugs are set up to print given data, and an exposed area or space, into which the type carriers may be moved and placed in printing position. In its present form, the device has been designed for use in printing identification characters and directions or memoranda upon cards, sheets, a continuous strip or the like, but it is not intended to limit its use to this particular purpose. One of the objects is to provide a series of type carriers (in which the type slugs are set up to form words or sentences) and one or more groups of type wheels containing type characters, such as numbers and letters, together with convenient means for moving the type carriers into printing position, and adjusting the type wheels, whereby an identification number and any selected information of data, contained on the type slugs stored in the device, may be printed upon a card, sheet, strip or the like. Another object is to provide an extremely simple, efficient and practical printing device, capable of performing the functions above set forth. With these and other objects and advantages in view this invention consists in the several novel features hereinafter fully set forth and claimed.

The invention is clearly illustrated in the drawings accompanying this specification, in which Fig. 1 is a plan, partly broken away, of a printing device embodying one form of the present invention; Fig. 2 is a vertical, longitudinal section taken on the line 2—2 of Fig. 1; Fig. 3 is a perspective view of a type carrier with type set therein and a fragment of an associated carrier guideway; Fig. 4 is a detail, vertical cross section taken on the line 4—4 of Fig. 2; and Fig. 5 is a detail, vertical cross section taken on the line 5—5 of Fig. 2.

Referring to the said drawings, the reference character 10 designates a base, which

as a preference, is of rectangular form and stands upon legs 11. The base is in the form of an open rectangular frame and its top is flat and horizontal, and the ends and sides thereof are covered by plates 12, 13, 60 and 14, which are secured to the base by screws or otherwise as desired. An open or exposed area or space 15 is left between the cover plates 12, 13, 14, and in this open area or space, the printing card, sheet, strip 65 or the like is accomplished. At the sides of this open space, under the cover plates 13, are storage places in which are stored a large number of type carriers 16, in which type slugs 40 are set up to print any data 70 or information desired. In the open space 15, at one or both ends thereof is one or more groups of type wheels 17, 18, which are provided upon their peripheries, such as the numbers 0 to 9 and letters of the 75 alphabet, and at the front of the device are finger pieces 19, operatively connected to the type wheels and furnishing means whereby the latter may be adjusted to bring any desired type characters thereof into 80 printing position. Above the open or exposed space 15, is a platen or impression making plate 20 which is rigidly secured to brackets 20¹, supported by a shaft 21 that is mounted in depressible arms 22 fulcrumed 85 at 23 upon ears 24. A handle 25, connected to one of the arms 22, is provided for depressing the impression plate, and coiled impression springs 26 are interposed between the base and arms 22 and act to raise the 90 arms 22 and therewith the impression plate. For the purpose of giving a parallel movement to the impression plate, I have provided parallel movement bars 27, fulcrumed to the base below the fulcrums 23 of the 95 arms 22, as at 28, and said bars 27 are pivotally connected, below the shaft 21, to arms 29, which are rigidly attached to the shaft. Obviously, any equivalent means may be employed for giving a parallel 100 movement to the impression making plate so that it may be brought down squarely upon the type to make impressions without blurring them. An impression pad 30 is secured in the lower face of the plate 20, and an ink ribbon 31 extends across the top of the exposed area 15, and is wound upon rollers 32 which are journaled in the side frame members of the base and have 105 heads or knobs 33 on their outer ends, by 110

which they may be turned to move the type ribbon so as to bring an unused part thereof over the printing area of the device.

In the embodiment of the invention illustrated, the type carriers 16 are slidably mounted in guide ways and capable of movement from an inoperative position to an operative, printing position. The guide ways may be formed of spaced, horizontally 10 extending bars 34, between which are placed inverted, U, bars 35. Said bars extend crosswise of the device and rest upon longitudinally frame members 36 that are secured to the base. Through the end portions 15 of the bars 34, extend rods 38 which tie the bars to brackets 37, that are screwed or otherwise securely fastened to the side frame members of the base.

The type carriers 16 may be in the form 20 of elongated box-like structures, for receiving the type slugs 40, and said type carriers and guide ways have co-operating means for preventing the type carriers from tilting therein. In the form shown, each 25 type carrier is provided with a substantially T shaped lug 41 on the lower side, which travels in a slot 42 in the bottom wall of the guide way which is formed by the inverted U, bar 35. The type slugs are locked 30 in the type carrier, as for instance by means of a threaded rod 43 which extends through the end walls of the type carrier and through holes or slots in the type slugs. A nut 44 threaded upon one end of the rod 35 and a shoulder on the other end of the rod, secure the parts together. The shoul- 35 dered end of the rod 43 is bent upward to provide a finger piece 45 by which the type carrier is shifted from one position to another, and slots 46 are provided in the cover 40 plates 13, through which said finger pieces extend into position to be conveniently taken hold of in manipulating the type carriers. When not in use, the type carriers 45 occupy positions under the cover plates, and they are moved into the exposed or open space 15 when they are to be used for printing upon the sheets. The ends of the slots 46 furnish means for limiting endwise move- 50 ment of the type carriers, and the inner ends serve to locate the carriers in their printing position. Printed slips are placed in the spaces between the slots 46, upon which are printed the data or other information 55 contained on the type slugs set in the adjacent type carriers. In the form shown, hooks 50 are struck up from the carrier plates adjacent to the ends of the slots 46, and serve to hold the printed slips in place. 60 The several groups of type wheels may be provided at one or both ends of the machine for printing identification numbers, and characters at both ends of the card or sheet. Each type wheel is provided with a 65 pinion or toothed member 51 at the side

thereof, which pinion spaces the type wheels of each group apart. The type wheels at each end of the machine, are mounted to rotate upon the shafts 52 and 53 which are secured on the frame bars 36, and the 70 groups of wheels are spaced apart by sleeves 54 which surround the shafts. Each type wheel is manipulated from an associated finger piece 19 at the front of the machine and as shown, this finger piece extends up 75 from a rack bar 55 which has rack teeth 56, 57 that mesh with the pinions or tooth members 51 of the type wheels. The rack bars 55 are slidably guided in cross bars 58 which are secured to the frame bars 36. 80 The fingers 19 project up through slots 59 in the cover plate 12, and indicating dials containing characters, corresponding to the characters on the type wheels, are placed adjacent to the slots, to indicate the stop- 85 ping places for the finger pieces. The characters adjacent the slots are so placed with reference to the characters on the type wheels, that the user may bring any de- 90 sired type character of any type wheel in- to printing position by moving the proper finger piece to the selected character on the dial.

In case it is desired to print upon a con- 95 tinuous strip of paper, a roll of paper 60 is provided which is mounted upon a rod 61, supported in ears 62 on the frame. The strip is drawn over the open or exposed space 15, and inserted underneath a tearing strip 63 on the cover plate 12.

In use, the several carriers are set up with type for printing directions, data or any information required in connection with work done in a factory, plant, or other establishment. In order to remove the type carriers from the device, the top or cover plates 13 are first removed from the frame. After the type carriers have been set with type, the type are locked in the type carriers by the lock device, the carriers are placed in the guide ways and the cover plates secured upon the base. The type carriers which are not used in connection with the printing of any sheet or sheets remain stored underneath the cover plates and only those that are needed for any job are moved into printing position. The type wheels are set to bring the desired characters there- 105 of into printing position to print the proper identification number by moving the fin- 110 ger pieces 19. If the printing is to be done upon cards, one, at the time, is inserted underneat the impression device and the latter is brought down upon the card, there- 115 by forcing it against the interposed ink ribbon. The card receives an impression from the type characters that are contained in the open or exposed area of the device. If a continuous strip is to be used, the end por- 120 tion thereof is drawn across the open or 125 130

exposed area and an impression made upon it, after which it may be pulled underneath the tearing strip 63 and that part which has been printed upon may be torn 5 away from the remainder.

It is obvious that by providing storing space in the device for a large number of set type, set to print desired information, the ones needed for printing any desired 10 information may be instantly moved into printing position and the others may remain stored away for future use. The device is extremely simple and can be operated by unskilled persons. It saves time 15 and labor and enables unskilled persons to print various data, information or directions quickly and dispense with the use of handwritten or typewritten work.

More or less variation of the exact 20 details of construction is possible without departing from the spirit of this invention; I desire, therefore, not to limit myself to the exact form of the construction shown and described, but intend, in the following 25 claims, to point out all of the invention disclosed herein.

I claim as new, and desire to secure by Letters Patent:

1. A printing device comprising a base, 30 having an exposed area for receiving and retaining in printing position, a plurality of type carriers containing set type slugs, said base having also storage spaces for receiving said type carriers, in combination with type 35 carriers, having type slugs set up therein, said type carriers being contained in said storage spaces and movable into said exposed area, in printing position therein, and an impression device arranged to be 40 brought down upon the type slugs located in printing position.

2. A printing device comprising in combination, a base having a series of transversely extending guideways secured therein, type carriers containing set slugs and 45 slidably mounted in said guideways, said type carriers being movable from an inoperative position to an operative, printing position in said guideways, and an impression device arranged to be brought down upon the type slugs that are in printing position.

3. A printing device comprising in a combination, a base having a series of transversely extending guideways secured therein, 50 type carriers containing set type slugs and slidably mounted in said guideways, said type carriers being movable from an inoperative position to an operative, printing

position in said guideways, and an impression plate arranged to be brought down upon the type slugs that are in printing position. 60

4. A printing device comprising in combination, a base having a series of transversely extending guideways secured therein, slotted cover plates covering the end portions of said guideways, type carriers containing set type slugs and slidably mounted in said guideways said type carriers having finger pieces extending out through slots in 70 the cover plates and being movable into an operative, printing position between said cover plates; and an impression plate arranged to be brought down upon the type slugs that are in printing position. 75

5. A printing device comprising in combination, a base having a series of transversely extending, slotted guideways secured therein, slotted cover plates covering the end portions of said guideways, type carriers containing set type slugs and slidably mounted in said guideways and having headed lugs extending through the slots of the guideways, said type carriers also having finger pieces extending up through the slots in the 85 cover plates, and an impression making device arranged to be brought down upon the type that are in printing position.

6. A printing device comprising in combination, a base having an exposed area, 90 slideable independently movable type carriers set with type slugs and independently movable into said exposed area, a group of type wheels in said exposed area, and individual means for setting the individual 95 type wheels of the group.

7. A printing device comprising in combination, a base having an exposed area, slideable type carriers containing set printing characters and movable into said exposed area, groups of type wheels in said exposed area, mounted on a supporting shaft, and each having a pinion at its side, and rack bars slidably mounted in said base and extending to the front thereof, said rack bars having rack teeth meshing with said pinions, and having finger places by which they are manipulated. 100

8. A printing device comprising in combination, a base having an exposed area and storage spaces at the sides thereof, slideable type carriers in said storage spaces movable into said exposed area, groups of type wheels at both ends of said exposed area, and means for setting the type wheels of each group. 110

MORRIS J. HOFFMAN.
